A. G. Burns ATTORNEY

UNITED STATES PATENT OFFICE.

LEWIS M. WILLIAMS, OF FORT WAYNE, INDIANA, ASSIGNOR TO THE UTENSILS COMPANY, A CORPORATION OF INDIANA.

IRONING MACHINE.

Application filed June 16, 1923. Serial No. 645,716.

To all whom it may concern:

Be it known that I, LEWIS M. WILLIAMS, a citizen of the United States of America, and a resident of Fort Wayne, in the county 5 of Allen and State of Indiana, have invented certain new and useful Improvements in Ironing Machines, of which the following is a specification.

This invention relates to improvements 10 in ironing machines particularly of that class in which a revolving feed roller is employed for pressing goods to be ironed against a heated smoothing element, and the objects thereof are to provide a gear mechanism, having a controlling means for throwing the feed roller into gear, which when manually released, will permit the feed roller to move automatically out of gear, and also out of engaging relation with the 15 smoothing element, and to provide a mechanism in connection with the feed roller by means of which the feed roller, when in operating position, will bear with more or less pressure against the smoothing element, 20 as adjusted.

These objects are accomplished by the construction illustrated in the accompanying drawings in which:

Fig. 1 is a perspective view of an ironing machine equipped with the present invention;

Fig. 2 is a detail view in perspective showing the feed roller and its support and also the adjustable mechanism by which it is caused to bear with more or less force 35 against the smoothing member;

Fig. 3 is an elevation showing the inner end of the feed roller and part of the gearing for actuating the same, there being parts 40 in section;

Fig. 4 is a front elevation of the head of an ironing machine including part of the gearing for actuating the feed roller, and means for throwing the same out of gear; 45 and

Fig. 5 is a plan view of the head and the transmitting gearing for the feed roller, there being parts broken away.

The characters appearing in the description 50 refer to parts shown in the drawings and designated thereon by corresponding characters.

The invention, as an example, is here shown applied to an ironing machine having a stand 1 with a gear case 2 at its

upper end upon which is secured an overhanging bracket 3 for the support of a rotating cylindrical smoothing member 4, the member being fixed upon a drive-shaft 5 that extends into the gear case. The shaft 60 5 is continuously rotated by gearing (not shown) of any suitable character contained in the gear case which is actuated through the medium of a drive-wheel 6 in the usual manner. A driving pinion 7 is mounted 65 upon a second drive-shaft 8 that is also actuated by the said gearing in the gear case.

Upon the front face of the gear case is a horizontally movable plate 9 through 70 which the drive-shaft 8 extends loosely, there being an elongated slot 10 in the plate, through which the shaft extends, to permit movement of the plate relative to said drive-shaft. A pair of lugs 11, that extend from 75 the face of the gear case adjacent the bottom and top of the plate, serve as guides to retain the plate in horizontal position. Upon the plate 9 is a fixed stud 12 that extends in parallelism with the drive-shaft 80 8 and has rotatably mounted thereon a pair of gears 13 and 14. The gear 13 has a pin 15 that extends loosely through a curved slot 16 in the gear 14, and the gear 14 has a pin 17 that is connected by a tension 85 spring 18 with the pin 15 so that the gear 14 may be retarded in its rotative movement to a limited extent relative to the gear 13.

On the gear case is a bracket 19 from 90 which extends a horizontal supporting shaft 20 upon which is rotatably mounted a tilting frame comprising brackets 21 and 22 that are fixed upon the respective ends of a pipe 23, the supporting shaft 20 extending 95 lengthwise through the pipe. The said tilting frame is also supported by means of a strut 24 that is connected at one end with a collar 25 on the pipe and at its opposite end with the stand 1.

In the swinging frame is mounted a horizontally disposed shaft 26, upon which is fixed a feed roller 27 that is located between the brackets 21 and 22, and upon the inner end of said shaft is fixed a gear 28 that has 100 engaging relation with the gear 14 which is mounted upon the stud 12 on the movable plate 9. When the plate 9 is in operating position the gear 13 meshes with the driving pinion 7, and as it is actuated thereby 110

movement is imparted through the medium of the pin 15 to the gear 14, thus causing the feed roller 27 to be actuated accordingly.

As a means to limit the downward movement of the swinging frame, a pipe 29 is pivoted to an arm 30 on the bracket 21, and a threaded rod 31 that is fixed on the strut 24 extends loosely into the pipe, there being a wing-nut 32 on the rod and also a buffer 33 that bears against the end of the pipe for adjustably limiting the sliding movement of the pipe on the rod.

A drag mechanism for the feed roller is arranged in connection with the swinging frame and consists of a lever 34 pivoted on the bracket 21 and provided with a pivoted shoe 35 at its upper end that frictionally engages the inner face 36 of the feed roller 27. A compression spring 37 is positioned between a lug 38 on the arm 30 and the pendant end of the lever 34 so that the shoe 35 will be held yieldingly against the inner face of the roller. Also, a threaded adjusting rod 39 extends through the lug 38 which may be turned so as to bear against the pendant end of the arm 34 and thus cause the shoe 35 to bear against the roller with more or less force according to the adjustment of the rod 39.

As a means for moving and holding the movable plate 9 into operating position a pivoted pedal 40 in the base 41 of the machine is connected by a rod 42 with a lever 43 that is pivoted on the gear case and which imparts movement to the plate 9 through the medium of an intermediate lever 44 that bears against a lug 45 on said plate. Also, a second means for moving and holding said plate in operating position, is provided by arranging a hand lever 46 so as to impart movement to the plate through the medium of a cam-bar 47 and a plunger 48 secured to or integral with the plate 9. By depressing either the pedal or the hand lever the plate 9 is moved so that the gears 13 and 14 will be brought into engagement respectively with the driving pinion 7 and the gear 28 on the feed roller shaft.

In the operation of the invention the smoothing member is heated in the usual manner, and motion is imparted to said member and the driving pinion by the gearing in the case 2. The plate 9 is then moved into operating position by depressing either the pedal 40 or the handle 46 so that the gears 13 and 14 are brought respectively into engagement with the driving pinion and the gear on the feed roller shaft so that movement is imparted to the feed roller. In moving the gears 13 and 14 into mesh with said pinion and gear simultaneously, the provision of this pin and slot connection of the gears 13 and 14 permits articulation of the gear 14 with the gear 28

without injury to the teeth of the gears. The action of the gear 14 in driving the gear 28 also has the tendency of lifting the swinging frame, and this tendency becomes more pronounced as rotary movement of the feed roller is resisted by the drag mechanism, and therefore, when the rod 39 is adjustably turned the feed roller will bear upwardly against the smoothing member with more or less force accordingly as said rod is adjusted.

When the pedal 40 is released, and the handle 46 is raised, the plate 9 is left free to move out of operating position, and owing to the weight of the swinging frame and the mechanism supported thereby, as well as the resistance of the feed roller to turning movement due to the drag mechanism, the gear 14 automatically passes out of engagement with the gear 28 causing the gear 13 and plate 9, through the medium of the stud 12, to move out of operating position.

What I claim is:

1. In an ironing machine having a smoothing member, a gear mechanism including a driving pinion, a plate movable relative to the pinion and having a stud thereon; a pair of gears on the stud, one of which is engageable with said pinion and has limited movement relative to its companion gear; a swingable frame including supporting means therefor; a feed roller movable into position to co-operate with the smoothing member supported by the frame and having a gear engageable with said companion gear; a drag mechanism on the swingable frame having engagement with the feed roller; means for varying the action of the drag mechanism on said roller; a means for limiting the downward swing of said frame; and gear engaging means for moving and holding said plate in operating position.

2. In an ironing machine having a smoothing member and a head including a driving pinion, a plate movable into and out of operative position, said plate having a stud; a pair of gears rotatably mounted on the stud, one of which has engagement with the driving pinion when the plate is in its operating position and which has limited movement relative to its companion gear; a supporting shaft projecting from the head; a swingable frame mounted upon the shaft; a feed roller supported in the frame and having a gear in connection therewith engageable with said companion gear; means to limit the swinging movement of the frame; manually operated means for moving said plate into its operating position; and means in operative relation with the smoothing member for actuating the swingable frame.

3. In an ironing machine having a smoothing member and a head including a

driving pinion; a movable gear supporting member including means for actuating the same; a pair of gears on said member, one of which is engageable with said pinion and has actuating relation with and limited rotative movement relative to its companion gear; a tension means for holding said gears in normal relative position; a swinging frame supported so as to have swinging movement; a feed roller supported in the frame and having a gear engageable with said companion gear; a shoe having frictional engagement with said roller; a spring pressed member supporting said shoe; and means for applying pressure adjustably to said spring pressed member.

4. In an ironing machine including a smoothing member and a driving head having a driving pinion; a pair of gears having limited rotative movement relative to each other, one of said gears being engageable with said pinion; a tension means in connection with said gears for holding said gears in normal relative positions; a rotatable feed roller movably mounted and having a gear in fixed relation therewith and engageable with the other of said pair of gears; a friction means applied to the feed roller so that the roller tends to move into bearing contact with the smoothing member

when it is rotated; and means for adjustably varying the pressure of said friction means against the roller.

5. In an ironing machine including a smoothing member and a driving head having a driving pinion; a pair of gears having limited rotative movements relative to each other, one of said gears being engageable with said pinion; a tension means in connection with said gears tending to hold said gears in normal relative positions; a rotatable feed roller movably mounted and having a gear in fixed relation therewith and engageable with the other of said pair of gears; and a friction means in connection with the movably mounted roller operable to move the roller into bearing contact with the smoothing member when it is actuated.

6. In an ironing machine including a smoothing member and driving gear, a swingable frame; a feed roller mounted in the frame and driven by said driving gear; a drag mechanism bearing against the feed roller and actuating the frame; and means for varying the pressure of the drag mechanism against the roller.

In testimony whereof I affix my signature.

LEWIS M. WILLIAMS.
